PRINTING PLATE CONTROLLED FEED
MEANS

Harmon P. Elliott, Watertown, Mass.

Application September 25, 1945, Serial No. 618,481

16 Claims. (Cl. 101—58)

1

This invention relates to improvements in printing machines of the general type which print from printing devices on which the data to be printed is carried, and in which the printing devices are moved to a printing position in a predetermined sequence for coaction with a printing mechanism. More particularly, the invention provides such a machine having provision for printing the data contained on one or a series of the printing devices as single items of a schedule or the like which may contain several items varying as to the number of lines of printing required for the items. For example, it may be desired to print a schedule comprising seven items requiring respectively twelve, two, three, eighteen, six, two and fifteen lines of printing. Inasmuch as each printing device is required to have a predetermined limited size, each is limited as to the number of lines of printable data it can carry, five lines of regular size printing being a practical maximum. Hence, it will be obvious that the items in the foregoing example which have twelve, eighteen, six and fifteen lines respectively will require three, four, two and three printing devices respectively to carry the required data, while the other items each may be printed from a single printing device. The invention provides a machine which prints in predetermined spaced succession items or paragraphs which may be complete on individual printing devices, and which prints multi-line items or paragraphs, the data for which may be on two or several printing devices.

It is an object of the invention to greatly extend the field for use of printing machines of the mentioned general type which print from a succession of printing devices on which the data to be printed is carried. The invention makes it possible and practical to print with such a machine data of any description in interspersed single and multi-line items or paragraphs which may be suitably spaced, one from another, on a card, a sheet or a continuous web.

Another object is to provide such a printing machine having provision for feeding the sheet, or other element being printed upon, one line space or a selected plurality of line spaces as determined by the condition of the printing device which at any time is in the printing position.

A further object is to provide in such a printing machine a relation of printing device feed to the sheet feed which is selectively responsive to indications on the printing devices, determining the number of single line spaces of advance

2

of the sheet in accordance with the number of lines of data contained on the printing devices arriving at the printing position.

It is, moreover, my purpose and object generally to improve upon prior printing machines and more especially such machines which print from a succession of data-bearing printing devices.

In the accompanying drawings:

Figure 1 is a top plan view of the major portion of a printing machine embodying features of the invention, the opposite end portions of the machine being broken away;

Figure 2 is an end elevation of the machine of Figure 1, looking from the left in Figure 1;

Figure 3 is a front elevation, on a larger scale, of the upper portion of the machine of Figures 1 and 2, with the sheet feeding means omitted;

Figure 4 is a cross-sectional view on line 4—4 of Figure 3 but omitting gear 148 and its bearing;

Figure 5 is a detail cross-sectional view on line 5—5 of Figure 1, on a larger scale;

Figure 6 is a detail cross-sectional view through the sliding-pin selector mechanism;

Figure 7 is a detail cross-sectional view looking at the right hand end of the mechanism of Figure 6;

Figure 8 is a detail elevation of the pin-re-setting mechanism;

Figure 9 is an elevation looking from the right at the mechanism of Figure 8;

Figure 10 is an enlarged cross-sectional detail on line 10—10 of Figure 5;

Figure 11 is a face view of a printing device in the form of a stencil, illustrative of printing devices suitable for use in my disclosed machine;

Figure 12 is a wiring diagram of the electrical control circuit; and

Figure 13 is a face view of a printed insurance schedule having a succession of items of varying line content uniformly spaced apart, as may be accomplished according to my invention.

Referring to the drawings, the machine as represented has a frame including a pair of end uprights 10 between whose upper ends extends the generally horizontal table 12 which supports a usual type of parallel grooved rails 14 which together constitute a track along which the printing devices 16, herein shown as stencils, are adapted to be moved. A stack of the stencils is held in a receptacle 18 above the right hand end of the track, and each stencil, as it becomes the lowermost one in the stack, is in position to be

engaged by a pusher 20 which is reciprocable

lengthwise of the track, in a well known manner, to move successive lowermost stencils out of the stack and along the rails 14. Preceding stencils are pushed by succeeding ones, and each ultimately arrives at a printing position, indicated generally at 22, and thence moves to the left hand end of the track and drops into a suitable receptacle (not shown).

The pusher 20 is reciprocated in a usual manner by a link 24 which has one end pivotally connected to the pusher and its other end pivotally connected to one arm 26 of a bell-crank lever whose other arm 28 engages in the cam slot 30 of a cam plate 32. The bell-crank lever is mounted on the fixed pivot 34 at the under side of table 12, and the cam plate 32 is fixed on a pivot-shaft 36 at the upper yoke-end of a fixed arm or strut 38. The pivot-shaft 36 is rocked by customary means not necessary to describe, thereby to effect reciprocating movements of the pusher.

The table 12 has an opening 40 therethrough at the printing position, across which the rails 14 extend, and a platen 42 and an impression roll 44 coact at the printing position to effect a printing from each stencil as it rests in the printing position. Or, if a particular stencil happens to be a blank one, an idle printing operation may be effected, as will later appear.

The platen 42 is pivoted at 43 and moved into and out of coacting relation to the stencil and the impression roll by a cam 46 which is secured to the pivot-shaft 36. The impression roll 44 is carried between and at the ends of arms 48 on the yoke member 50 which has a fixed pivot at 52 and which has the depending arm 54 whose lower end is adjustably connected at 56 to the actuating lever 58 for the pivot-shaft 36. Hence, movements of the actuating lever 58, rock the pivot-shaft 36 and thereby move the yoke member 50 about its pivot 52 to swing the impression roll into and out of engagement with a stencil at the printing position. Also, rocking of the pivot-shaft reciprocates pusher 20 and actuates platen 42, as previously explained.

My present invention provides means for associating as a single printed item or paragraph data which may be carried on two or more successive stencils, and for providing a uniform spacing of successive printed items or paragraphs some of which may have only a one or two line content and others of which may have five, ten or more lines of content. It is desirable to have single-line spacing of the content of each item or paragraph and a double-line spacing of successive items or paragraphs.

I attain this desirable and important result by a selective feed of the sheet or other element which is being printed upon, means being provided which selectively feeds the sheet one, two, three, four or five single line spaces depending upon the number of lines of data contained on the stencil which at any time is in the printing position.

The machine herein represented is designed for printing schedules of a sort used by insurance companies, and such a schedule is represented in part in Fig. 13. However, it will be obvious that data of any description which can be carried on stencils or comparable printing devices may be printed on individual sheets or cards or on continuous webs in accordance with the invention.

Referring to Fig. 5, the sheets to be printed are manually inserted to printing position from 75

in front of the machine, a sheet 60 being shown in Fig. 5 with its inner portion engaged between the feed rolls 62, 64 and with its forward edge against a guide 66 which is adjustable at the front of the table 12. The lower feed roll 64 is carried at the inner end of a lever 68 which is pivoted at 70 on a bracket 72 depending from the table. The outer arm of this lever has a pin-in-slot connection at 74 to link 76 which is pivoted at 77 at the under side of table 12. The lower end of link 76 is connected through link 78 to one arm of a bell-crank lever 80 which is pivoted at 81 on bracket 82 and whose other arm is connected through rod 84 to a treadle 86. A spring 87 yieldingly urges the lever 68 to keep feed roll 64 pressed against roll 62 or against a sheet 60 engaged between them.

Prior to insertion of a sheet 60, treadle 86 is depressed to retract feed roll 64 so that the sheet may be freely inserted between the rolls and adjusted to bring its outer edge against the guide 66, the latter having been suitably adjusted for a desired placement of the printing relative to the inner edge of the sheet 60. The treadle is then released and roll 64 moves back into feeding engagement with the sheet.

The amount the sheet 60 will be fed following each printing coaction of platen 42, impression roll 44 and the stencil 16 which is in printing position, depends upon the number of lines of data that is carried on that particular stencil. According to the invention, the margin of each stencil 16 has a notch 88 therein (Fig. 11) and the position of the notch on any particular stencil is indicative of the number of lines of data which is contained on that stencil or indicative of a blank stencil suitable merely as a spacer. In the disclosed embodiment, each stencil has five notch positions, indicated respectively in Fig. 11 at 88, 89, 90, 91 and 92. However, the stencil of Fig. 11 has a notch cut therein only at the position 88 because the stencil has five lines of data thereon. A blank stencil, used for a spacer, will have its notch at the position 92 whereas a stencil having a single line of data on it would have its notch at the position 91. Two, three and four line stencils would be notched respectively at positions 90, 89 and 88, assuming that each is a complete item which is to be spaced from the next succeeding line to be printed. If a stencil has only part of an item which must be completed from one or more succeeding stencils, with no spacing of the matter on the respective stencils, the first five lines of the item will be on the first stencil and it will be notched at 88 for a five-line advance of the sheet following a printing from this stencil. The next succeeding stencil, bearing another portion of the item, will follow directly so that a printing from it will constitute a continuation of the first-printed matter, without a space left between. On the other hand, if a five-line stencil has a complete item thereon so that its printed matter should be spaced from a next succeeding printing, its notch will be at 88 as before, for a five-line advance of the sheet, but a blank spacer stencil, with notch at 92, will follow to provide the spacing of items. A four-line stencil is notched at 88 the same as a five-line stencil, so that a five-line advance of the sheet occurs for spacing its printed matter from a next succeeding printing.

Mounted at the front of the machine, opposite the printing position 22, are five electric switches 94, each with a push-button 95 (Fig. 5), and each with a resilient actuating arm 96 carrying a roller

97 at its free end. Each switch is carried on a sheet metal bracket 98 which conveniently may be secured to the forward one of the track rails 14. A lever 100 is pivoted intermediate its ends at 102 on each bracket 98 with one arm of the lever extending inward over the forward rail of the track and with its other arm extending under the roller 97 of a switch actuating arm 96. Preferably the end of the outer arm is equipped with a roller 104. The rail 14 has a hole 106 under each inwardly projecting arm of the levers 100, and each lever 100 has a pin 108 at its inner end depressible into a hole 106 in the track by counter-clockwise rocking of the lever 100. A stencil 16 at the printing position 22 will have its notch registering with some one of the holes 106, and depression of a lever pin 108 into that hole results in the pin continuing downward in the notch thereby permitting a rocking of that particular lever 100 sufficiently to move its outer end enough to effect closing of the associated switch 94. The other four depressed pins 108 encounter solid marginal parts of the stencil and rocking of their levers 100 is arrested before they will have effected a closing actuation of their associated switches 94.

Rocking of the individual levers 100 to depress the pins 108 into the rail holes 106 is occasioned each time the impression roll 44 moves to printing position. To this end, the arms 49 which carry the impression roll have secured thereto at 110 a bracket including a bar portion 112 which extends in front of the roll 44 and from end to end thereof. Five tubes 114 are mounted on the bar 112 and each tube has a yieldable pin 116 projecting out of its lower end in position to engage the inner end of a lever 100 each time the impression roll 44 moves to printing position.

Engagement of a pin 116 with a lever 100 rocks the lever, but if the lever pin 108 engages a solid margin of stencil, the pin 116 can yield against its backing spring 118 as best seen in the detail showing of Fig. 10.

Each of the switches 94 controls an electric circuit to one of the five solenoids 120 which are mounted in a suitable casing 121 above the table 12 as seen in Figs. 3 and 4, and as indicated in the circuit diagram of Fig. 12. Also they are shown in Fig. 1 where the top of casing 121 is omitted. The armature of each solenoid is connected to one of the five depending arms 122, 124, 126, 128 and 130, each of which is pivotally suspended from a rod 132 which is supported in brackets 134. When a solenoid 120 is energized by closing of its control switch 94, the armature of the solenoid draws the lower end of the depending arm to which it is connected to the right as viewed in Fig. 3, for a purpose to be described, and a spring 136 is connected to each depending arm for returning the arms following de-energization of the associated solenoid 120.

A disk 138 is fixed to the short shaft 140 which is rotatably mounted in the bearings 142, 144 on a fixed bar 146 extending in spaced general parallelism with table 12. A spur gear 148 is fixed to the left hand end of shaft 140, as viewed in Fig. 3, and meshes with a spur gear 150 on the shaft 152 of the feed roll 62. Hence, any rotation of disk 138 effects a sheet-feeding rotation of the feed roll 62.

Disk 138 has a multiplicity of pins 154 extending loosely therethrough all around its margin and the lower end of each depending arm 122, 124, 126, 128 and 130 stands opposite one of the pins 154, as best seen in Figs. 3 and 4. Referring to Fig. 3, the pins project beyond both faces of the disk 138 and are headed at their ends so that their sliding movements are limited.

Referring now to Figs. 6 and 7, a ratchet wheel 156 is fixed to shaft 140 back of disk 138, and a pawl 158 is carried on a member 160 which is freely rotatable on shaft 140. A spring yieldably urges the pawl into engagement with the teeth of ratchet wheel 156 so that, in Fig. 7, clockwise movements of the pawl-carrying member 160 effects clockwise rotation of disk 138 and shaft 140, and the pawl 158 rides idly over the ratchet teeth upon counter-clockwise movement of member 160. A second pawl 164, at the opposite side of the ratchet wheel, prevents any counter-clockwise movement of disk 140.

The member 160 which carries the actuating pawl 158 has the general shape as best seen in Fig. 7, with a head 161 at its end, which mounts the slideable re-setting pin 162. Pin 162 extends through the head 161, with a stop pin 164 limiting its movement in direction away from disk 138, and with a spring 166 engaging the stop pin 164 and yieldingly maintaining the re-setting pin 162 in its position of Fig. 6. The head 161 has the portion 163 (Fig. 6) projecting toward disk 138 beyond the adjacent end of the re-setting pin in the latter's position of Fig. 6, constituting a surface which, upon swinging of member 160, engages whichever pin 154 of the disk 138 may have been pushed through the disk by the selector mechanism.

Referring now to Figs. 1 and 4, the member 160 is represented in Fig. 4 by dotted lines behind the disk 138, and a link 168 (Figs. 1 and 4) is connected at one end to member 160 and at its other end to the lower arm of a lever 170 pivoted at 172 on bracket 174 reaching out from a fixed support 176. The upper arm of lever 170 is connected to one end of a link 178 whose opposite end portion is slotted at 180 for reception of a pin 182 carried at the end of an arm 184 fixed at one end of shaft 186, which latter is rotatably supported in bearings 188 on the fixed support 176. A coil spring 190 has one end connected to the upper arm of lever 170 and its other end engaging pin 182 for yieldingly holding the pin at one end of slot 180 as seen in Fig. 4. The opposite end of shaft 186 has fixed thereon a pin-carrying arm 192 whose pin 194 engages in the slot 196 at one end of a link 198. The other end of link 198 is pivotally mounted at 200 on a bracket 202 carried on the yoke member 50. A coil spring 204 is anchored at one end at bracket 202 and has its other end engaging pin 194 to hold it yieldingly at one end of slot 196 as in Fig. 4.

Hence, each time yoke 50 moves to bring impression roll 44 into printing position, link 198 is carried with it, and shaft 186 is rotated counter-clockwise, in Fig. 4, the spring 204 being strong enough to hold pin 194 against movement in its slot 196, so that arm 192 is rocked to rotate shaft 186. Rotation of shaft 186, through arm 184 and its pin-in-slot connection to link 178, causes swinging of lever 170 clockwise, as viewed in Fig. 4, causing movement of link 168 to the left, and counter-clockwise swinging of member 160 on shaft 140. Assuming that the stencil which is in printing position is like that of Fig. 11, having five lines of data and a notch at the position 88, a movement of the impression roll 44 to printing position will result in depression of the switch-actuating lever 100 which is associated with the notch position 88, and that lever pin 108 will be depressed into the notch 88, permitting a switch-closing switch of the lever 100. In Fig. 1, the particular

60 movement of link 168 to the left, and counter-clockwise swinging of member 160 on shaft 140. Assuming that the stencil which is in printing position is like that of Fig. 11, having five lines of data and a notch at the position 88, a movement of the impression roll 44 to printing position will result in depression of the switch-actuating lever 100 which is associated with the notch position 88, and that lever pin 108 will be depressed into the notch 88, permitting a switch-closing switch of the lever 100. In Fig. 1, the particular

lever 100 and switch 94 thus actuated are those at the extreme left in the group of five. The pins 108 of the other four levers 100, when depressed by the same movement of yoke 50, engage solid portions of the margin of the stencil and their levers 100 are arrested before they move switch-closing amounts. Hence, only the switch 94 farthest to the left in Fig. 1 is closed and a circuit is closed only through the solenoid 120 whose armature is connected to the depending arm 130 (Fig. 4). This arm consequently is drawn toward disk 138, and the pin 154 opposite the lower end of arm 130 is pressed rearward through the disk so that it has substantial projection at the rear side. As previously explained, the member 160 will have been swung counter-clockwise in Fig. 4 to a position at the left of the series of five pins 154 which stand opposite the depending arms 122, 124, 126, 128, and 130.

As yoke 50 moves back to the left in Fig. 4, after a printing, member 160, through link 168, is swung in clockwise direction about shaft 140 until its head portion 163 (Fig. 6) engages the pin 154 which has been pushed rearward by depending arm 130. The pin 154 stops member 160 but the return movement of yoke 50 continues, with the pins 182, 194 yielding along their slots 180, 196 in their respective links 178 and 198. The mechanism is now set for the maximum or five-line feed of the sheet 60 as the yoke 50 next moves to carry the impression roll 44 to printing position, the pawl 158 being engaged with the teeth of ratchet wheel 156 so that the ratchet wheel and shaft 140 will be rotated counter-clockwise as viewed in Fig. 4, and clockwise as viewed in Fig. 7, until the head 161 of member 160 strikes the fixed stop pin 206 (Fig. 7). As viewed in Fig. 7, the member 160 always moves clockwise into engagement with pin 206 during each printing movement of yoke 50 and impression roll 44. However, the amount of its clockwise movement to this stop position depends upon which of the depending arms 122, 124, 126, 128 or 130 has acted to push a pin 154 of disk 138 rearward. For example, if the pin opposite depending arm 122 (Fig. 4) is the one that is pushed rearward, the member 160 will move only into engagement with that pin on a return movement of yoke 50, and the subsequent ratchet-rotation of shaft 140 will only be such as to feed the sheet 60 one line space. Similarly, operation of depending arm 124 will effect a two-line feed of sheet 60, and operation of depending arms 126 and 128 will effect respectively a three-line and a four-line feed of sheet 60.

Before the part 163 of member 160 moves away from a pin 154 against which member 160 was stopped on a return movement of yoke 50, the particular pin 154 is re-set by being pushed forward to its starting or inactive position. This is accomplished by the re-setting pin 162 in member 160 which, at that time, will be opposite the active pin 154 of disk 138. The return movement of yoke 50, releases the switch-actuating lever 100 so that its pin 108 is retracted, switch 94 opened and depending arm 130 returned by its spring 136 to normal position. Hence when the yoke 50 is at rest in its rearmost non-printing position of Fig. 5, all of the switches 94 are open. However, a similar switch 208 is mounted under table 12 on the fixed bracket 210, and a cam element 212 is carried on the cam plate 32 which actuates the stencil pusher 20. As the cam plate 32 moves upward to effect advance of a different stencil to the printing position 22, the cam element 212 closes the switch 208 to complete a cir-

cuit through a solenoid 214 (Figs. 3, 8 and 9) whose armature is connected to one arm 218 of a bell-crank lever pivoted at 220. The other arm 222 of the bell-crank extends to a position opposite the end of re-setting pin 162, so that, as the armature of solenoid 214 is drawn inward upon energizing of the solenoid, the bell-crank is rocked in direction to push re-setting pin 162 to the left in Fig. 8. This causes the re-setting pin to thrust the opposite pin 154 of disk 138 to the left to a re-set position. Upon de-energizing of solenoid 214, a spring 224 returns the bell-crank to its inactive position of Fig. 8 where it may rest against a suitable stop 226.

A manual switch 228 is shown in Fig. 3, and in the diagram of Fig. 12, for cutting out the automatic selector feed mechanism when desired.

From the foregoing description, it will be obvious that I have greatly extended the field of utility of printing machines of the general type which print from a succession of data-bearing printing devices, such as stencils. Whereas the prior machines have been capable of printing continuous items with single-line spacing, they have been limited to items running not over five lines of data, such as could be borne on a single printing device or stencil. Also the prior machines have been incapable of printing a succession of items of varying line-number content, with uniform spacing of the successive items. The invention makes it possible to print continuing multi-line items or paragraphs with single-line spacing, and to print a succession of items or paragraphs of varying line-number content, with each item or paragraph equally spaced from the next preceding and next succeeding item or paragraph.

While the illustrated embodiment of the invention provides for one, two, three, four and five line feed-advances of the sheet 60 or other element being printed upon, this has been determined only by the limited size of the stencils employed which conveniently can receive a maximum of five lines of regular size type. Obviously, a larger size of stencil could receive more lines of data thereon, in which case a corresponding larger number of notch positions would be provided on the stencils, with an equal number of pin-actuators and control switches 94.

With the five-notch-position stencils as shown, if it is desired to provide a space between the printed matter of two successive five-line stencils, this may be done conveniently and simply by inserting a blank stencil between them having a notch at the position 92 (Fig. 11).

Briefly summarizing the operation of the disclosed machine, the operator may first close switch 228 to condition the electrical system for automatic operation. Treadle 86 is then depressed to spread feed roll 64 away from feed roll 62. The pin-in-slot connection at 14 between the roll-carrying lever 68 and pivoted link 76 is such that the treadle remains depressed until pressure is applied to the treadle at the opposite side of its pivot. A sheet 60 (Figs. 5 and 13) may now be inserted between the feed rolls 62, 64 and its outer edge is brought against the guide 66 to properly position it for an initial printing, after which the feed roll 64 is moved back so that the inner portion of sheet 60 is gripped between the two feed rolls 62, 64. Assuming a succession of stencils 16 in the track rails 14, with one at the printing position 22, the platen 42 and impression roll 44 move into printing coaction with the

stencil to print data contained thereon on the sheet 60. As the yoke member 50 carries the impression roll 44 to printing position, the yieldable pins 116 engage the levers 100 and all five of them are rocked to depress their pins 108 into the holes 106 in the forward rail 14. Whichever lever pin 108 finds a notch in the stencil margin continues downward and that lever 100 is rocked sufficiently to cause closing actuation of its associated switch 94. The other four lever pins 108 strike solid portions of stencil margin and are arrested before their levers 100 rock sufficiently to close their switches 94. The switch 94 which has been actuated closes a circuit to the proper one of the solenoids 120 so that the proper depending arm 122, 124, 126, 128 or 130 is actuated to push a pin 154 of disk 138 rearward.

As the yoke 50 moves back from printing position, the circuit to the particular solenoid 120 is opened and member 160 is swung clockwise (Fig. 4) until its head portion 163 (Fig. 6) strikes the particular pin 154 which has been pushed through disk 138. Continued backward movement of yoke 50 ultimately causes closing of switch 208 and energization of solenoid 214 which acts to actuate re-setting pin 162 of member 160 thereby to return the rearwardly pushed pin 154 to its original position. Also, as yoke 50 moves back from printing position, pusher 20 is actuated to advance a new stencil to the printing position 22.

When yoke 50 again moves forward to bring impression roll 44 to printing position, the pawl 158 on member 160 rotates ratchet wheel 156 and shaft 140 counter-clockwise (Fig. 4) until member 160 comes against the fixed stop 206. The amount of this rotation of the ratchet wheel 156 and shaft 140 depends upon which pin 154 stopped the member 160, and the rotation of shaft 140, through the gears 148, 150 effects corresponding but opposite sheet-feeding rotation of the feed-roll 62, to advance sheet 60 one, two, three, four or five line spaces depending upon the number of lines of data which was contained on the stencil last printed from.

As sheet 60 is advanced the proper amount during movement of yoke 50 toward printing position, the location of the notch in the new stencil at the printing position will result in closing of the proper switch 94 and the cycle as explained is repeated.

I claim as my invention:

1. In a printing machine, means for moving uniformly-dimensioned data-bearing printing devices in succession to a printing position, printing mechanism for coacting with a printing device at the printing position thereby to effect a printing on a sheet element from the printing device, each said printing device having at one of a plurality of indicating locations thereon, an indication indicative of the number of units of advance of the sheet element which should follow a printing from that printing device, means for intermittent feed of a sheet element to be printed upon at the printing position, and means responsive to said indication on the printing device in the printing position for setting said feeding means for feeding said sheet element one predetermined number of units of advance when said indication is at one of said indicating locations and for feeding said sheet element a different predetermined number of units of advance when said indication is at another of said indicating locations.

2. In a printing machine, printing mechanism, and means for moving uniformly-dimensioned

data-bearing printing devices in succession into coacting relation to the printing mechanism thereby to effect successive printings on a sheet element from successive printing devices, each said printing device having, at one of a plurality of indicating locations thereon, an indication indicative of a predetermined number of units of advance of the sheet element which should follow a printing from that printing device, and means, operative after a printing operation and prior to each succeeding operation of the printing mechanism, for feeding the sheet element varying amounts depending upon which of said plurality of indicating locations has a said indication thereon on the printing device last printed from.

3. In a printing machine, printing mechanism, and means for moving data-bearing printing devices in succession into coacting relation to the printing mechanism thereby to effect successive printings on a sheet element from successive printing devices, all of said printing devices having uniform dimensions, and each printing device having, at one of a plurality of indicating locations thereon, an indication indicative of a predetermined number of units of advance of the sheet element which should follow a printing from that printing device, means for advancing the sheet element following a printing thereon from a printing device, and means responsive to the indication on each printing device arriving in succession at the printing mechanism for varying the amount of the advances of the sheet element with variation of the locations of the indications among said plurality of indicating locations on each of the succession of printing devices.

4. In a printing machine, printing mechanism, and means for moving data-bearing printing devices in succession into coacting relation to the printing mechanism thereby to effect successive printings on a sheet element from successive printing devices, means for advancing the sheet element any of a predetermined number of single-line units of advance following a printing thereon from a printing device, and means selectively positioned on each printing device indicative, by its position on the device, of the number of units of advance of the sheet element which should follow a printing from that printing device, said indication on the printing device last printed from coacting with said sheet element advancing means to determine the number of units of advance which will precede a next succeeding printing.

5. In a printing machine, printing mechanism, and means for moving uniformly-dimensioned data-bearing printing devices in succession into coacting relation to the printing mechanism thereby to effect successive printings on a sheet element from successive printing devices, means for advancing the sheet element following each printing thereon from a printing device, there being means on each printing device indicative by its position on the printing device of the number of single-line units of advance of the sheet element which should follow a printing from that printing device, and selector means responsive to a said indicating means of a printing device and operative to effect one single-line unit of advance of the sheet when the indicating means is at one position on the printing device last printed from and to effect a plurality of single-line units of advance of the sheet when

11

said indicating means is at a different position on the printing device last printed from.

6. In a printing machine, printing mechanism, and means for moving uniformly-dimensioned data-bearing printing devices in succession into coacting relation to the printing mechanism thereby to effect successive printings on a sheet element from successive printing devices, means for advancing the sheet element following each printing thereon from a printing device, each said printing device having an indication thereon indicative of the number of single-line units of advance of the sheet element which should follow a printing from that printing device, and means responsive to the indication on a printing device at the printing mechanism for selectively effecting one single-line unit of advance of the sheet element when said indication is at one position on the printing device and any of two, three, four and five single-line unit advances of the sheet element when said indication is respectively at a second, third, fourth and fifth position on the printing device.

7. In a printing machine, means for moving data-bearing printing devices in succession to a printing position, printing mechanism operable at the printing position for effecting successive printings from different printing devices, means for feeding a sheet element which is to be printed upon and for advancing the sheet element selectively one, two and multi-line units of advance following each of successive printing operations of the printing mechanism, the individuals of said succession of printing devices being uniform in size and each printing device having indicating means thereon at one of a plurality of indicating positions indicative of the number of line units of advance of the sheet element which should follow a printing from that printing device, said feeding means coacting with the said indicating means on the printing device in the printing position to provide any of a one-unit, two-unit and multi-unit advance of the sheet element depending upon the position of the indicating means on said printing device in the printing position.

8. In a printing machine, means for moving data-bearing printing devices in succession to a printing position, printing mechanism operable at the printing position for effecting successive printings from different printing devices, means for feeding a sheet element which is to be printed upon and for advancing the sheet element selectively one, two and more single-line units of advance prior to successive different printing operations of the printing mechanism, and means responsive to the printing device in the printing position for setting the feeding means for advancing the sheet element any of one, two and more single-line units of advance prior to a printing from the next succeeding printing device arriving at the printing position.

9. In a printing machine having means for advancing data-bearing printing devices in succession to a printing position, and printing mechanism for coacting with a printing device at the printing position to effect a printing therefrom, means for advancing a sheet element which is to be printed upon a varying number of units of advance prior to each printing by the printing mechanism, each of the succession of printing devices being uniform in size, and each having indicating means at one of a series of indicating positions thereon, and means coacting with a said indicating means on the printing device at the printing position for selecting the number

12

of units of each advance of the sheet element according to the location of the said indicating means on the succession of uniform printing devices.

10. In a printing machine having means for advancing data-bearing printing devices in succession to a printing position, and printing mechanism for coacting with a printing device at the printing position to effect a printing therefrom, means for advancing a sheet element which is to be printed upon a varying number of units of advance prior to each printing by the printing mechanism, said means comprising selector mechanism at the printing position, including a plurality of selector elements depressible against a printing device in the printing position, means for depressing all of said selector elements in response to each printing operation of the printing mechanism, each said printing device having an opening therein indicative by its position on the printing device of the number of lines of data on the printing device, and a said opening in each printing device arriving at the printing position being in register with one of said depressible selector elements whereby that selector element is depressed into said opening while the other selector elements are arrested by solid portions of the printing device, and means responsive to depression of a said selector element into a said opening in a printing device for setting said sheet element advancing means for an advance of the sheet element a number of units of advance at least equal to the number of lines of data on the printing device in the printing position.

11. In a printing machine, means for advancing data-bearing printing devices in succession to a printing position, means for intermittently advancing a sheet element at the printing position, printing mechanism for effecting a printing on said sheet element from printing devices of the said succession, each printing device having an indication thereon indicative by its position on the printing device of the number of lines of data contained thereon, a plurality of selector elements in positions for coaction each with a said indication in a different position on a printing device at the printing position, and means responsive to a said coaction of a selector element with a said indication on a printing device for setting said sheet element advancing means for an advance of the sheet a number of units of advance corresponding to the number of lines of data on the printing device at the printing position.

12. In a printing machine having means for printing from data-bearing printing devices which are advanced in succession to the printing means, the combination therewith of means operative prior to each printing by the printing means for advancing a sheet element which is to be printed upon a number of units of advance varying with variation of the number of lines of data on the printing device last printed from, said sheet element advancing means including a plurality of depressible selector elements depressible into engagement with the printing device at the printing means, means responsive only to a predetermined amount of depression of a said selector element for setting the sheet element advancing means for a selected number of units of advance of the sheet element following a printing from the printing device which is at the printing means, each printing device having an opening therein indicative by its position on the printing

device of the number of lines of data thereon, and said opening in each printing device arriving at the printing means registering, according to its position, with a particular one of said selector elements, whereby that element, upon depression, finds the said opening and is depressed further than the other selector elements thereby to effect the said setting of the sheet element advancing means.

13. In a printing machine having means for printing from data-bearing printing devices which are advanced in succession to the printing means, the combination therewith of means operative prior to each printing by the printing means for advancing a sheet element which is to be printed upon a number of units of advance varying with variation of the number of lines of data on the printing device last printed from, said sheet element advancing means comprising a feed roll and mechanism operative selectively for rotating the feed roll one predetermined fraction of a rotation when the printing device last printed from has no data thereon and for rotating the feed roll two of said fractions of a rotation when a said printing device has one line of data thereon and increasing amounts with increase of the number of lines of data on the printing device at the printing means, each printing device having an indication thereon indicative by its position on the device of the number of said predetermined fractions of a rotation of the feed roll which should follow a printing from each printing device, and said mechanism including selective means responsive to a said indication on the device at the printing means.

14. In a printing machine having means for printing from data-bearing printing devices which are advanced in succession to the printing means, the combination therewith of means operative prior to each printing by the printing means for advancing a sheet element which is to be printed upon a number of units of advance varying with variation of the number of lines of data on the printing device last printed from, said sheet element advancing means including depressible selector elements operative on the printing device at the printing means, and each printing device having an opening therein indicative by its position on the printing device of the number of lines of data contained thereon and adapted to register with some one of said selector elements whereby that element finds said opening when depressed and is depressed more than the other elements, means for depressing said elements during each printing operation of the printing means, and means responsive to the greater depression of that selector element which finds an indicator opening in the printing device for setting the sheet element advancing means for an advance of the sheet element a number of units of advance corresponding to the indicated number of lines of data on the printing device at the printing means.

15. In a printing machine having means for printing from data-bearing printing devices which are advanced in succession to the printing means, the combination therewith of means operative prior to each printing by the printing

means for advancing a sheet element which is to be printed upon a number of units of advance varying with variation of the number of lines of data on the printing device last printed from, each printing device having an indication thereon indicative by its position on the device of the number of units of advance of the said sheet element which properly should follow a printing from that printing device, and said sheet element advancing means including selector elements operative on the printing device at the printing position for finding the said indication of the particular printing device which is at the printing position, and means responsive to that one of the selector elements which finds the indication on the printing device for setting the sheet element advancing means for an advance of the sheet element the number of units of advance indicated as proper following a printing from that particular printing device.

16. In a printing machine having means for printing from data-bearing printing devices which are advanced in succession to the printing means, the combination therewith of means operative prior to each printing by the printing means for advancing a sheet element which is to be printed upon a number of units of advance varying with variation of the number of lines of data on the printing device last printed from, each printing device having an indication thereon indicative by its position on the device of the number of units of advance of the said sheet element which properly should follow a printing from that printing device, and said sheet element advancing means including selector elements for finding the indication on the printing device which is at the printing mechanism, a member rotatable in one direction to set the sheet element advancing means and rotatable in the other direction to advance the sheet element a selected number of units of advance, and means responsive to that one of the selector devices which finds the said indication on the printing device at the printing means for determining the amount said rotatable member shall be rotated in the setting direction thereby to select the number of units of advance the sheet element shall be advanced following a printing from the particular printing device.
